DESIGN FOR A MILK BOTTLE

Ernest H. Pihlstrom, Denver, Colo.

Application July 26, 1943, Serial No. 110,769

Term of patent 14 years

To all whom it may concern:

Be it known that I, Ernest H. Pihlstrom, a citizen of the United States, residing in the city and county of Denver and State of Colorado, have invented a new, original, and ornamental Design for Milk Bottles, of which the following is a specification, reference being had to the accompanying drawing, forming part thereof.

In the drawing:

Figure 1 is a side elevation of a milk bottle, showing my new design; and

Figure 2 is a side elevation taken at right angles to that shown in Figure 1.

The dominant features of my design are shown in full lines on the drawing.

I claim:

The ornamental design for a milk bottle, as shown and described.

ERNEST H. PIHLSTROM.
